UNITED STATES PATENT OFFICE

ALOIS KNOTZ, OF GRAZ, AUSTRIA

FEED DEVICE FOR THE PAPER STRIP OF ADDING MACHINES AND CASH REGISTERS

Application filed September 20, 1929, Serial No. 393,875, and in Austria September 26, 1928.

This invention relates to a feed-device for the paper strip of adding machines and cash registers in particular of such types as have a tilting printing roller, and consists essentially in the provision of a toothed rod tiltably mounted on the carrier of the printing roller and adapted to engage in the teeth of a cog wheel mounted on the feed-roller of the paper strip in one direction only, while in the other direction the teeth slip past each other without engaging. For the purpose of ensuring that the length of strip fed forward at each operation of the device be reliably and accurately constant, the end of the toothed rod is made to co-operate, on the carrier being returned to its original position, with one arm of a pawl the other arm of which engages in a ratchet wheel mounted on the feed-roller.

An example of the embodiment of the invention in a cash register consisting of an adding machine with multiple printing apparatus is shown in the accompanying drawings, in which:

Fig. 1 is a side elevation of the adding machine.

Fig. 2 is a side elevation of the back portion of the adding machine in one position of the printing and feeding apparatus.

Fig. 3 is the same side elevation with the printing and feeding apparatus in another position.

Fig. 4 is a section of a portion of the feed device.

Fig. 5 is a front elevation of the feed device.

The adding machine 1 is provided with an operating handle 2 which is situated outside the casing 3 of the cash register and is connected to a cog-wheel 4 which co-operates with an intermediate wheel 5 and a further cog-wheel 6. The carrier 8 of a printing roller 9 which on being tilted strikes against the type on the wheel 10 is mounted on the fulcrum-pin 7 of the cog-wheel 8 (Fig. 2).

A collecting drum 12 is provided on extensions 11 of the carrier 8 for the registering strip 13 which is led from a supply roller (not shown) over the printing roller to the collecting drum. A lever 14 is mounted on the machine 1 above the pin 7, in the same plane as a ratchet-wheel 17 attached to the printing roller 9, and drawn by a spring 15 against a stop 16 on the machine. The collecting drum 12 and the printing roller 9 are connected by an endless band 18. The connecting piece 21 of two cheek-plates 22 and 23 bent up at right angles to the connecting piece is fastened by means of the screws 20 to the back plate 19 of the machine. A feed roller 24 is mounted in the cheek-plates 22, 23, and a pressure roller 26 is mounted with a certain amount of play in the arms 27, 28 and guided in the slits 25 which are disposed radially to the feed roller. Above the pivot points 29, 30 of the arms 27, 28 the double-armed levers 33, 34 are mounted at 31, 32 having their shorter arms resting on the set-screws 35, 36, while the other arms are connected to the arms 27, 28 to which they are disposed roughly parallel by means of tension springs 37, with the result that the pressure roller 26 is pressed against the feed roller 24. A shaft 38 mounted in the cheek-plates carries at each side a disc 39, 40 in contact with the arms 27, 28 and provided with pins 41, 42 which co-operate with the arms. The disc 40 is provided with a handle 43 the movement of which from the position shown in Fig. 1 to that shown in Fig. 3 causes the pins to be pressed against the arms 27, 28 and the roller 26 to be brought out of contact with the roller 24.

The axle 44 of the roller 24 carries a ratchet-wheel 45 and a cog-wheel 46 the teeth of which are similar in form to those of a ratchet-wheel. This cog-wheel co-operates with a toothed rod 48 which is mounted on the carrier 8 at 47 and is provided with teeth corresponding to those of the cog-wheel. The

engagement of the toothed rod in the cog-wheel 46 is maintained by a lever 51 which is pressed against an extension 50 of the toothed rod 48 by means of a spring 49. A double-armed lever 52, 53 mounted on the cheek-plate 22 represents with its one arm a pawl 54 (Figs. 2 and 4) and is provided on its other arm with a plate 55 bent up at right angles and adapted to cooperate with the ratchet wheel 45 or with the toothed rod 48. In the position of the carrier 8 shown in Fig. 2 the lever 52, 53 rests against the stop 56 in consequence of the weight of the plate 55. A guide 57 for the paper strip intended for the printing of receipt tickets is fastened to the machine opposite the point of contact between the rollers 24 and 26. This paper strip 58 comes from a supply roller (not shown), passes between the rollers and through the guiding funnel 57, and comes to a guiding device 60 for the ink ribbon 61. The strip passes through a loop formed in the ribbon, and through a slit 62 of the guiding device to a tear-off comb 63, where it passes out of the machine. A window 64 permits of the reading of the figures typed on the registering strip.

The operation of the device is as follows:

After the amount of the sum taken has been set by means of the keys the handle 2 is pulled over towards the front, with the result that the carrier 8 is simultaneously tilted by means of the wheels 4, 5, and 6 from the position shown in Fig. 1 to that shown in Fig. 2, and the printing roller 9 strikes against the type on the wheel 10, so that the figures set are printed simultaneously on the receipt strip 58 and on the registering strip 13. The tilting of the carrier brings the ratchet wheel 17 into contact with the lever 14 which is tilted about its pivot and by virtue of the location of its pivot eccentrically to the fulcrum-pin 7 of the carrier slips over a number of the teeth of the ratchet-wheel 17. The toothed rod 48 is moved during the tilting of the carrier into the position shown in Fig. 2, its teeth sliding over those of the cogged wheel 46 attached to the feed roller by virtue of the shape of the teeth and of the checking of the feed roller by the pressure roller. The arm 53 of the lever 52, 53 hits against the stop 56 and frees the pawl 54 from the ratchet wheel 45. The return movement of the handle 2 tilts the carrier 8 back to its original position. The toothed rod 48 now engages in the teeth of the cog-wheel 46, the feed roller is turned and the printed paper strip 58 is correspondingly fed forward, after which the portion projecting beyond the tear-off comb 63 may be detached. The end of the toothed rod hits against the turned up plate of the lever 53, so that the pawl 54 is instantly engaged in the ratchet wheel 45. This provides the ad-

vantage of ensuring that the paper strip, which is often printed on the reverse side with advertising matter, be always fed forward to exactly the same extent, so that the lines of detachment exactly coincide with the spaces between the printed matter on the reverse side of the strip.

The lever 14 also takes part in the return movement of the carrier 8 and since it is kept in contact with the ratchet wheel 17 by the spring 15 it forces this wheel round through a certain portion of a turn, by virtue of the above-mentioned particular location of its pivot. This rotation is transmitted by the band 18 to the collecting drum 12 which draws the paper strip 13 forward to a corresponding extent.

The insertion of the paper strip 58 can be facilitated by bringing the pressure roller (Fig. 3) out of contact with the feed roller, which is effected by tilting the handle 43.

The pressure of the roller 26 against the feed roller can be adjusted by means of the set-screws 35, 36, and the feed-length of the paper strip by altering the size of the wheel 46 or of the feed roller 24.

I claim:

1. A feed device for the paper strip of adding machines and cash registers comprising a tiltable holder for the printing roller, a toothed rod tiltably mounted on the said tiltable holder, a driving roller for the strip, a cog-wheel attached to the said driving roller, the teeth of the toothed rod being adapted to engage in the teeth of the said cog-wheel in one direction only and to slip past them when moved in the other direction, and a double-armed lever, the one arm of which being adapted to co-operate with the end of the said toothed rod when the holder is tilted back to its original position, the other arm of the said double-armed lever being adapted to engage in a ratchet wheel attached to the said driving roller.

2. A feed device for the paper strip of adding machines and cash registers comprising a tiltable holder for the printing roller, a toothed rod tiltably mounted on the said tiltable holder, a driving roller for the strip, a cog-wheel attached to the said driving roller, the teeth of the toothed rod being adapted to engage in the teeth of the said cog-wheel in one direction only and to slip past them when moved in the other direction, a pressure roller, and spiral springs for pressing the said pressure roller against the driving roller, the said springs being connected to the one arm of double-armed levers the other arms of which being in contact with set-screws for adjusting the tension of the said spiral springs.

3. A feed device for the paper strip of adding machines and cash registers comprising a tiltable holder for the printing roller, a toothed rod tiltably mounted on

the said tiltable holder, a driving roller for the strip, a cog-wheel attached to the said driving roller, the teeth of the toothed rod being adapted to engage in the teeth of the 5 said cog-wheel in one direction only and to slip past them when moved in the other direction, a pressure roller, spiral springs for pressing the said pressure roller against the driving roller, and adjustable means for 10 holding one end of the spring..

In testimony whereof I affix my signature.
ALOIS KNOTZ.
